OUTDOOR FOOD TRAY

Sander Charles Nestegard, White Bear Lake, and Jack E. Wies, New Brighton, Minn., assignors to Marsan Industries Inc., White Bear Lake, Minn., a corporation of Minnesota

Filed Feb. 26, 1969, Ser. No. 15,924

Term of patent 14 years

Int. Cl. D7—99

U.S. Cl. D44—10

FIG. 1 is a top plan view of an outdoor food tray showing our new design;

FIG. 2 is a bottom plan view;

FIG. 3 is a front elevational view;

FIG. 4 is a right side elevational view; and

FIG. 5 is a left side elevational view.

We claim:

The ornamental design for an outdoor food tray, substantially as shown.
